FILTER PAPER

Southwick W. Briggs, Montgomery County, Md., and William A. Brazerol, Washington, D.C. (both % Stone Filter Co. Incorporated, 900 Franklin St. NE, Washington, D.C. 20017)

Filed Dec. 28, 1964, Ser. No. 83,165

Term of patent 14 years

(Cl. D16—1)

FIG.1

FIG.2

FIG.3

FIG.4

FIG. 1 is a top plan view of a portion of a sheet of filter paper showing our new design;

FIG. 2 is a fragmentary perspective view showing the top surface of filter paper embodying the new design;

FIG. 3 is a fragmentary perspective view showing the bottom surface thereof; and

FIG. 4 is an enlarged fragmentary cross section taken along line 4—4 of FIG. 2.

The design is repeated horizontally and vertically.

We claim:

The ornamental design for filter paper, as shown and described.
